UNITED STATES PATENT OFFICE

155,572

DESIGN FOR A VIBRATING APPARATUS FOR TREATING HUMAN BODIES

Paul Bertholin, New York, N. Y.

Application August 21, 1948, Serial No. 148,237

Term of patent 14 years

(Cl. D83—1)

To all whom it may concern:

Be it known that I, Paul Bertholin, a citizen of the United States, residing at 340 West 88th Street, New York, in the county of New York and State of New York, have invented a new, original and ornamental Design for a Vibrating Apparatus for Treating Human Bodies, of which the following is a specification, reference being had to the accompanying drawing constituting a part hereof:

Fig. 1 is a top plan view of a vibrating apparatus for treating human bodies, embodying my new design;

Fig. 2 is a front elevational view; and

Fig. 3 is a side elevational view thereof.

I, claim:

The ornamental design for a vibrating apparatus for treating human bodies, substantially as shown.

PAUL BERTHOLIN.
